DEVICE TO FORM PIN CURLS

Anne Lee Wyatt, Los Angeles, Calif.

Application May 6, 1940, Serial No. 333,629

6 Claims. (Cl. 132—33)

The device of this invention relates to the hair dressing art in general, and in particular to that division of the art which has for its purpose the development of ringlets of hair commonly termed pin curls, for the reason, that after formation the ringlets or curls are secured in place by means of hair-pins until the curl assumes a fixed contour, or the curl may be worn with its supporting hair-pins in position depending only upon the choice of the party concerned.

Ordinarily pin curls are formed with the fingers and after formation are secured in position by hair-pins, and while this method is satisfactory if performed by a hair-dresser who is skilled in the art, nevertheless it is most unsatisfactory when one tries to dress her own hair as falls to the lot of most people.

Being aware of the limitations and difficulty in forming pin curls upon one's own head, I have contrived to provide means to facilitate this form of work.

Therefore, it is a prime object of the present invention to provide a simple and easily used device to give strands of hair ring-like form and while in this position to apply a hair-pin thereto in such manner as to retain the ringlet after removal of the accessory used in its formation.

Another object of the invention is to provide a pin curl accessory which may be used to clamp the near outer ends of strands of hair and which is thereafter adapted to be rotated whereby the hair is wound upon the outer side of the accessory to form a curl or ring, the accessory being so formed as to admit of insertion of hair-pins to clasp the curl thus formed at several places whereby its shape is retained after withdrawal of the accessory.

A further object of the invention is to provide a device which is adapted to clamp strands of hair between half portions thereof and which is then turned or rotated around the longitudinal axis of the device whereby the hair is wound upon the outer side of the device to form a curl or ring, the device being formed with slots, in the end adjacent the ring of hair, whereby hair-pins may be inserted across the diameter of the device to clasp and hold the ring or curl thus formed after which the device is finger pressed to release the hair from their clamped position.

A still further object of the invention is to provide a pin curl forming device which is simple in construction, low cost, rugged, and reliable and which is easily used.

Other objects, features, and advantages of the invention may be apparent from the accompany-

ing drawing, the specification, and the subjoined claims.

In the drawing:

Figure 1 is a side-elevation showing the device of this invention.

Figure 2 is a view of the device set forth in Figure 1, the view is taken along line 2—2, Figure 1.

Figure 3 is a side-elevation of the upper half 10 of the device of this invention.

Figure 4 is a view taken along line 4—4, Figure 3 showing the half-portion described in Figure 3.

Figure 5 is a side-elevation of the lower half- 15 portion of the device of this invention.

Figure 6 is a view taken along line 6—6, Figure 5 showing the half-portion of the device shown in Figure 5.

Figure 7 is a sectional elevation taken along 20 line 7—7, Figure 1.

Figure 8 is another sectional elevation taken along line 8—8, in Figure 1 showing further detail of construction.

Figure 9 is a view substantially in plan and 25 is taken along line 9—9, Figure 1 showing construction of the curler.

Figure 10 is a sectional view taken along line 10—10, Figure 1 and showing strands of hair clamped between the half-portions of the device 30 and with the strands then wound around the curler, and with hair-pins inserted through the diameter of the device to hold the curl in shape.

Figure 11 is a figure which is illustrative of the curl formed with the device of this invention, hair-pins in this case are retained to hold the curl in form after withdrawal of the curl forming accessory.

Figure 12 is a view illustrative of a curl formed with the device of this invention, both the device and temporarily used hair-pins being removed to better show the form of the curl which is symmetrical in all detail.

The device of this invention 18, as shown in Figure 1, comprises the half-portions 20 and 22 which are complementary to each other and which are joined by means of a pintle 24.

The portion 20 is first formed as a blank punching die stamped from suitable sheet metal, and after being placed in a forming die is bent transversely to form a channel-shaped member that is approximately semi-circular in cross section with its sides 28 and 30 lying substantially 180 degrees apart in a uniform degree of curvature. The product thus formed is best illustrated in Figs. 3 and 4. Elongated slots 32 are punched

from the stock 26 at the time the blank is first punched therefrom. Openings 34 are formed in the blank at the time of its formation and form bearing points for the pintle 24.

The half-portion 22 is in part formed in the same manner as the portion 20, that is, it is formed with a semi-circular end 36 having elongated slots 38 and an opening 40 which is complementary to the openings 34 and is likewise adapted to form bearing points for the pintle 24 which may be either tubular or solid for its sole purpose is to form a pivotal connection between the half-portions 20 and 22. However the portion 22 essentially distinguishes from the portion 20 in that it is formed with an extension 42 which rises above the plane of the semi-circular portion 36 and is bent in the forming die to form a closed circle as shown in Figures 5 and 6. Reference to the drawing will show that the line 44 is coincidental with a horizontal plane taken across the device, and that this line forms a clamping point or point of engagement for the portions 20 and 22, the line 44a being coincidental with the half-portion 20 while the line 44b is coincidental with the half-portion 22 and reference to Figures 1 and 2 will show that these lines or structural edges are intended to be brought into alignment and hence form stops against the action of spring 46 which presses outwardly against the finger grip ends 48 and 49, however, the extension 42 as shown in dotted lines in Figure 1, also forms a stop against pressure of the spring 46 and therefore eliminates any tendency for the line 44a and 44b to slip or move laterally and hence be brought into lapped relation, for as will be shown in the description of operation it is essential that these lines or edges be brought into pressure contact to clamp strands of hair which are temporarily held therebetween as shown in Figure 10 at 50.

The following matter forms a description of use in forming a pin curl with the device of the present invention.

With the device assembled as shown in Figure 1, it is only necessary to apply inwardly directed pressure upon the finger grip ends 48 and 49 to spread the clamping ends 21' and 23' which fulcrum upon the pintle 24, thereby enabling insertion of the free ends 50 of strands of hair 52. Thereafter the device 18 is rotated around its longitudinal axis which is substantially parallel to the scalp, thereby winding the hair 52 around the exterior surface of the device so that it builds up into an annular ring-shaped roll as shown in Figure 10.

The device is now upended with its longitudinal axis pointing toward the head and with the circular forward end of the device resting gently against the scalp. By means of pressure of the thumb and finger, the strand or lock of hair previously wound upon the forward portion of the device is now pushed to the forward end of the device so as to occupy a position immediately against and parallel with the adjacent portion of the scalp, thereby forming an annular or ring-shaped body of hair, and the device is now rotated so as to more tightly wind the annular body of hair thereupon.

The legs of a hairpin which normally bear directly against each other as a result of the resiliency of the metal of which the hairpin is formed, are now separated a slight distance and said separated legs are passed through two of the diametrically opposite slots in the forward portions of the jaws of the device and said pin manipu-

lated so as to receive between them the ring-shaped body of hair and when the legs of the hairpin are released, the circle of hair is gripped at two oppositely disposed points and with said body of hair and the hairpin lying substantially flat against the head.

To further grip and hold the annular body of hair in proper position, a second hairpin formed of resilient metal is inserted through the other two diametrically arranged slots in the forward portion of the device so as to grip the ring-shaped body of hair at points ninety degrees from the points engaged by the first inserted pin, and thus the coiled body of hair is gripped at four points ninety degrees apart as illustrated in Fig. 11.

The forward end of the device is now withdrawn from the ring-shaped body of hair which is retained in its annular form by the clamping effect of the legs of the hairpins and the latter are permitted to remain on the body of hair until the same becomes set, after which the pins are removed, leaving a perfectly formed ringlet or pin curl.

If the hair has been treated with certain hair dressings the curl 54' thus formed will naturally last a greater length of time because of stiffness imparted thereto by the dressing, otherwise the curl will last through a period proportional to natural susceptibility of the hair to curling.

Thus it will be seen that I have provided a pin curl forming device that is relatively simple in construction, inexpensive of manufacture and very effective in performing the functions for which it is intended.

The particularly desirable and advantageous feature of my improved pin curler is the provision of a plurality of pairs of diametrically arranged slots which extend from the forward ends of the jaws of the device a short distance rearwardly through those portions of the jaws upon which the strand of hair that is to be curled, is wound and which slots enable the legs of resilient hairpins to be inserted through the forward portion of the curling device to grip the curled body of hair and firmly retain the same in its desired form while becoming set and further, said slots permitting the curling device to be readily withdrawn without disturbing the curl of hair and the hairpins that are applied thereto.

In conclusion, it may be stated as being obvious that various and sundry changes and modifications may be effected in practicing the invention in departure from the showing of the drawing and description as given, without however, departing from the true spirit of the invention as defined by the scope of the appended claims.

I claim:

1. A pin curl forming device comprising a pair of substantially identical members assembled to form a mandrel, the forward portions of said members being substantially half round in cross section, means pivotally connecting said members to each other intermediate their ends, the side edges of those portions of said members forwardly of the point of pivotal connection normally bearing directly against one another so as to provide cooperating edges for engaging and gripping an interposed strand of hair, those portions of the members to the rear of point of pivotal connection providing handles and said jaws being provided in their forward portions between their hair gripping side edges with longitudinally disposed parallel slots that extend rearwardly from the forward ends of said jaws.

2. A pin curl forming device as set forth in claim 1 and a spring associated with the rear portions of the members forming the pin curler for normally maintaining the jaws in closed position.

3. A pin curl forming device as set forth in claim 1 and with the slots in one jaw being disposed diametrically opposite the slots in the other jaw.

4. A pin curl forming device comprising a substantially cylindrical member divided on a medial longitudinal line to form a pair of substantially identical parts, each part comprising a jaw and a handle, each jaw being substantially semi-circular in cross section, with the side edges of the forward portions of said jaws bearing directly against one another so as to engage and grip an interposed strand of hair, means pivotally connecting said parts to each other intermediate their ends, yielding pressure means associated with said parts for normally maintaining the jaws in closed position, with the side edges of the forward portions thereof bearing directly against one another and each jaw provided with a longitudinally disposed slot open at the forward end of the jaw and extending rearwardly from said forward end. 25

5. A pin curl forming device as set forth in claim 4 and with the slot in one jaw being disposed diametrically opposite the slot in the other jaw.

6. A pin curl forming device comprising a substantially cylindrical member divided on a medial longitudinal line to form a pair of substantially identical parts, each part comprising a jaw and a handle, each jaw being substantially semi-circular in cross section, with the side edges of the forward portions of said jaws bearing directly against one another so as to engage and grip an interposed strand of hair, means pivotally connecting said parts to each other intermediate their ends, yielding pressure means associated with said parts for normally maintaining the jaws in closed position, with the side edges of the forward portions thereof bearing directly against one another, each jaw provided in its forward portion with a plurality of slots open at the forward ends of said parts and extending rearwardly from said forward ends and with the slots in one jaw being disposed diametrically opposite the slots in the other jaw. 20
